UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK, A CORPORATION OF NEW YORK

FASTENER

Application filed December 20, 1930. Serial No. 503,802.

The present invention relates to fasteners and more particularly to the type employing a member slideable on a strap, belt or the like, to obtain different adjustments thereon, this 5 application being a division in part of an application filed by me on the 7th of June, 1928, Serial No. 283,646. An object of this invention is to provide a construction in which the slideable member may be made inexpensively 10 from a single piece of sheet metal without any substantial waste of material.

To this and other ends, the invention consists of certain parts and combinations of parts, all of which will be hereinafter described, the novel features being pointed out in the appended claims.

In the drawings:

Fig. 1 is a view of a man's garter embodying this invention;
20 Fig. 2 is a front view of the slide member;
Fig. 3 is a rear view of the slide member; and
Fig. 4 is a sectional view through the slide member in position on the strap of the 25 garter.

In the drawings is shown a garter for men having its leg encircling portion formed of two strap pieces 1 branched from a pad 2 from which the garment clasp 3 is suspended. 30 On one strap piece is secured a loop 4 for engaging a slide member on the other strap piece.

The slide member is formed from a single piece of sheet material and comprises three 35 parallel bars 5, 6 and 7, separated by two parallel slots 8 and 9, equi-distant from opposite sides of the slide and each having its outer side nearer the adjacent side of the slide than the inner side of the two slots are 40 to each other, so that the bar 6 is wider than the bars 5 and 7. At the upper and the lower edges of the slide are provided rearwardly projecting cross pieces or flanges 10 and the slots 8 and 9 extend to these flanges. 45 The bars 5, 6 and 7 are arranged on a curve which throws the bar 6 slightly in advance of the bars 5 and 7. A strap piece 1 passes through the slots 8 and 9 in rear of the bars 5 and 7 and in front of the bar 6, and this 50 strap piece has a longitudinally extending

series of openings or holes 11 into any one of which may enter a rearwardly extending tongue 12 formed on the inner edge of the bar 5. This tongue is formed from metal cut from the slot 8 and the recess 13 in the bar 6. Ordinarily the friction of the strap on the bars 5, 6 and 7 will hold the slide in an adjusted position, but the tongue 12 insures the slide against movement on the strap. 55

In order that the slide may be engaged by the loop 4, an anchoring device is provided on the slide in the form of a hook 14 in the form of a U shaped member having its ends connected to the bar 6 substantially at the middle of the latter, the central portion of the member lying in rear of the bar 6 in spaced relation to the latter and the arms being curved and connecting to the bar 6. The U shaped hook has its central portion 60 formed of metal cut from the slot 9 and its 65 ends from metal cut from the bar 6.

The slide construction is not only neat in appearance but it has a maximum strength for a structure made from sheet metal and no material waste is present in its construction. The strength is obtained through the rearwardly projecting side flanges which also act to hide the inner ends of the hook when the slide is viewed from the side. 75

What I claim as my invention and desire 80 to secure by Letters Patent is:

1. A slide formed from sheet metal and having a slot through which a strap may pass, and an anchoring device arranged on the rear of the slide to one side of the slot, 85 said anchoring device being formed from a U shaped member cut from the stock of the slide, the central portion being formed from metal cut from the slot and the end portions being cut from metal to one side of the slot 90 and having bends therein which throw the central portion in the rear of the slide and to one side of the slot.

2. A slide for straps consisting of sheet metal having a portion partly cut therefrom to provide a slot for the passage of a strap and lateral slots, the portion thus separated being substantially of U shape and bent upon itself to provide a hook in the rear of the slide.

3. A sheet metal slide for straps having opposite edge portions flanged, and having spaced slots terminating adjacent the flanges and forming a middle and side bars, the slide having a tongue at the outer side of one of the slots, and having the portion cut therefrom to form the other slot of substantially U shape and bent upon itself to provide a hook in the rear of the slide and upon the same side thereof as the flanges.

EDWIN S. MIX.
